UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

INKING DEVICE FOR ADDRESSING MACHINES.

Application filed October 18, 1920. Serial No. 417,579.

To all whom it may concern:

Be it known that I, CLIFTON CHISHOLM, a citizen of the United States, residing at Cleveland, in the county of Cuyahoga and 5 State of Ohio, have invented a certain new and useful Improvement in Inking Devices for Addressing Machines, of which the following is a full, clear, and exact description, reference being had to the accompanying 10 drawings.

This invention relates to a mechanism for inking address plates in an addressing machine as they are passing from the supply to the impression members.

15 One of the objects of the invention is to arrange the plate and the mechanism that supplies the ink thereto in such manner that only the printing characters will be inked, thereby preventing smudging of the paper, 20 which would happen if other portions of the address plate, or its holder, were inked. At the same time, this mechanism protects the transfer roller from being injured by undesirable contact with the plate holder.

25 Other features of the invention relate to carrying a proper supply of ink in an absorbent roller, and the ready loading of such roller, and to maintaining proper adjustment between the supply roll and the transfer roll, 30 and between the transfer roll and the plate.

The invention is hereinafter more fully explained in connection with the drawings illustrating an approved embodiment thereof.

In the drawings, Fig. 1 is a sectional elevation of my ink mechanism; Fig. 2 is an end view thereof; Figs. 3, 4 and 5 are vertical sections on the correspondingly numbered lines of Fig. 1.

35 The frame of the machine shown comprises a suitable bed 10 and a pair of standards 11. On the inner sides of the standards are horizontal troughs 12, in which travel conveyer chains 13 adapted to carry the address plates A thru the machine. The address plate at the inking mechanism is supported by rollers 20 mounted on a shaft 21, which has bearings in the standards.

40 Directly above the address plate is a composition roller 30 mounted on the shaft 31, which has bearing blocks 32 housed in openings 33 in the standards. As shown in Fig. 3, the blocks are guided on their vertical sides, while movement is allowed in a vertical direction. The blocks are pressed downwardly by compression springs 35 mounted

in facing cavities respectively in the upper part of the block and the under part of a cap plate 15 extending across and forming the top of the standard 11. Alignment of the bearings with the shaft axis is maintained by vertical pins 37 carried by the blocks and extending into vertical openings 18 in the standards.

45 Above the composition roller is a felt supply roll 40. This roll is composed of a large number of annular pieces of felt mounted on a perforated tube 41. At each end flanged bushings 42 and 43 screw into the tube 41 and serve to compress the felt rings, suitable washers 44 being placed between the flanges 45 of the bushings and the felt. At one end the bushing 42 has rigidly secured to it, a stud 45, which forms a gudgeon for carrying the roller. At the other end a gudgeon 46 is provided, but this gudgeon has a screw 47 threaded engagement with the bushing 43, so that it may be readily removed for loading the roller. Each gudgeon has its shank occupying a vertical slot 19 in the cap member 15. Suitable collar portions 48 on the 50 gudgeons serve to center the roller. At their outer ends the gudgeons have knurled knobs to enable convenient handling.

55 The sectional construction of the felt roller described enables it to be cheaply made, and repaired from time to time by the substitution of new felt rings, and enables also its convenient loading whenever desired, the roller being simply removed and held vertical, the gudgeon 46 screwed out, the ink supplied and the gudgeon returned to position.

60 To maintain a proper pressure between the felt roller and the composition transfer roller, I provide a pair of hooks 51 pivotally secured at 52 to the blocks 32, and having bent over ends 53 which bear against the shanks of the two gudgeons. Set screws 54 in these ends hold the hooks in place. By this means, the felt roller is 65 maintained with desired snugness against the composition roller and the two float as a unit as the address plates travel beneath the composition roller and raise it.

65 An important feature of the invention is the provision of means to maintain the composition roller out of contact with the address plate, except when the printing characters are in position for inking. To effect this, I provide bearing rollers 60 on the 70

shaft 31, and I form depressions *a* in the hollow ribs forming the end portions of the plate opposite the region of the printing characters. When the plate is passing thru the machine, the portion thereof in advance of the depression *a* engaging the bearing rollers 60 raises the composition roller so that it cannot contact with the plate holder, thus, it is neither injured itself, nor does it smudge the holder. Just before the type portion of the plate reaches the composition roller the depressions *a* in the plate holder are presented to the bearing rollers 60. Then the composition roller under the action of the springs 35 moves downwardly and contacts with the type characters. As soon as these characters have been inked the portion of the plate holder beyond the depressions *a* again raises the composition roller to inactive position.

It should be noted that the plate holder having the edge ribs with top depressions illustrated herein forms the subject matter 25 of my application No. 410,710, filed September 16, 1920.

Having thus described my invention, I claim:

1. The combination, with an inking roller, 30 of bearing rollers coaxial therewith, and an address plate having raised and depressed portions adapted to coact with the bearing rollers.

2. The combination, with an inking roller, 35 of bearing rollers coaxial therewith, and an address plate having hollow ribs with raised and depressed portions adapted to coact with the bearing rollers.

3. The combination, with an inking roller, 40 of bearing rollers coaxial therewith, an address plate having ribs with depressed portions opposite the region of the printing characters, and means for supporting the address plate, and for feeding it with the 45 depression tangential to the bearing rollers.

4. The combination, with an inking roller, 50 of bearing rollers coaxial therewith, an address plate having raised and depressed portions adapted to coact with the bearing rollers and rotary supporting rollers on the under side of the plate opposite the ink roller.

5. The combination, with an inking roller, 55 of bearing rollers coaxial therewith, an address plate having raised and depressed portions adapted to coact with the bearing rollers, chains for advancing the plate, and means for supporting the chains below the bearing rollers.

6. The combination, with an inking roller, 60 of bearing rollers coaxial therewith, an address plate having raised and depressed portions adapted to coact with the bearing rollers, chains for advancing the plate and 65 troughs for supporting the chains below the

bearing rolls, and rotary supporting rollers on the under side of the plate opposite the ink roller and projecting between the troughs.

7. In an inking device, the combination 70 with means for supporting an address plate having depressed edged portions, of an inking roller having bearing rollers at its opposite ends, and springs pressing the inking roller and bearing rollers toward the plate. 75

8. The combination, of means for supporting an address plate having depressed portions opposite the ends of its printing portion, a shaft, an inking roller thereon, bearing rollers on the shaft adapted to engage the plate adjacent the line of the depressed portion, slideable bearing blocks in which said shaft is mounted, and springs pressing the bearing blocks toward the plate. 80

9. The combination, of means for supporting an address plate having depressed portions opposite the ends of its printing portion, a shaft, an inking roller thereon, bearing rollers on the shaft adapted to engage the plate adjacent the line of the depressed portion, slideable bearing blocks in which said shaft is mounted, and springs pressing the bearing blocks toward the plate, troughs beneath the bearing rollers, 90 and conveyor chains in said troughs supporting the edge portions of the plates in contact with the bearing rollers. 95

10. The combination, of means for supporting an address plate having depressed portions opposite the ends of its printing portion, a shaft, an inking roller thereon, bearing rollers on the shaft adapted to engage the plate adjacent the line of the depressed portion, slideable bearing blocks in which said shaft is mounted, and springs pressing the bearing blocks toward the plate, means supporting the edge portions of the plates in contact with the bearing rollers, and rotary supports for the intermediate portion of the plate. 105

11. The combination, with means for supporting an address plate, of a transfer inking roller adapted to coact with the plate, a supply roller coacting with the inking roller, 115 means for locking the supply roller and the inking roller together whereby they will be compelled to float as a unit, and springs pressing said inking roller into contact with the plate. 120

12. The combination, with a transfer inking roller, movable bearing blocks in which the same is mounted, springs acting on said bearing blocks, a supply roller contacting with the transfer roller and having projecting gudgeons, and hooks connecting said gudgeons with the bearing blocks. 125

13. The combination, with a transfer inking roller, movable bearing blocks in which the same is mounted, a supply roller con- 130

tacting with the transfer roller and having projecting gudgeons, and hooks pivoted to the bearing blocks and having their upper ends overhanging the gudgeons and carrying screws bearing against the same.

14. The combination with an inking roller, of means to convey address plates, one after the other, past the inking roller, a series of address plates, and means including surface irregularities on each address plate to permit said inking roller to advance toward said address plate only when the printing characters are beneath said inking roller.

15. 15. In combination, means to convey an address plate to printing position, an inking roller, said address plate comprising a body portion having printing characters thereon, and means operated by a part of said body

portion of the address plate to cause the inking roller to move toward said address plate to ink the latter.

16. In combination, means to convey address plates, an inking roller, and means on the inking roller and coaxial therewith for coacting with each address plate to permit the inking roller to move toward the address plate to ink the printing face of the latter.

17. The combination with an inking roller, of means to convey address plates, one after the other, past the inking roller, and a series of address plates having surface irregularities thereon whereby the address plate and inking roller are permitted to coact.

In testimony whereof, I hereunto affix my signature.

CLIFTON CHISHOLM.
